UNITED STATES PATENT OFFICE.

MORRIS G. ROSENTHAL, OF CINCINNATI, OHIO.

LABEL-FEEDING MEANS FOR AUTOMATIC LABEL AND PATCH STITCHING MACHINES.

1,389,598.

Specification of Letters Patent. Patented Sept. 6, 1921.

Application filed September 15, 1920. Serial No. 410,447.

To all whom it may concern:

Be it known that I, MORRIS G. ROSENTHAL, a citizen of the United States, residing at Cincinnati, county of Hamilton, State of Ohio, have invented certain new and useful Improvements in Label-Feeding Means for Automatic Label and Patch Stitching Machines, of which the following is a specification.

10 This invention relates to improvements in label feeding means for automatic label and patch stitching machines. The invention relates particularly to label feeding means adapted to deliver labels under the 15 label presser foot of a machine like that appearing in Rosenthal *et al.* Patent No. 1,293,554 of February 4, 1919.

20 The objects of the invention are to simplify the delivery or feed mechanism of the labels to such a machine. A further object is to provide a semi-automatic means for thus placing the labels in position, the same being manually controlled except for release devices, thereby eliminating much of the 25 mechanism and eliminating obstructions to the operator without materially lessening the speed of the operations.

30 I accomplish the objects of my invention by the devices and means described in the following specification. The invention is clearly defined and pointed out in the claims.

35 A structure which is a preferred embodiment of my invention is clearly illustrated in the accompanying drawing, adapted especially to the machine of the patent above referred to, in which:

40 Figure I is a perspective view of the feed means as applied to a sewing machine of the class indicated, the parts of the sewing machine being shown in fragment.

Fig. II is a side elevation from the left of the view of Fig. I.

45 Fig. III is a detail transverse sectional view taken on line 3—3 of Figs. I, II and IV, showing details of the fingers of the label follower.

50 Fig. IV is an enlarged detail longitudinal sectional view through the feed mechanism taken on line 4—4 of Figs. I and III, showing the feed means in the position which it assumes after a label has been stitched and withdrawn, or at the beginning of operations.

55 Fig. V is a longitudinal sectional view similar to Fig. IV showing the label follower as it appears after it has been manually

withdrawn to receive a label, the label being shown in position to be fed under the label shoe.

Fig. VI is a similar longitudinal sectional view showing the label fed in position for stitching, the withdrawn position of the latch lever being indicated by dotted lines.

In the drawing the sectional views are taken looking in the direction of the little 65 arrows at the ends of the section lines and similar numerals of reference refer to similar parts throughout the several views.

Considering the numbered parts of the drawing, 1 is the bed of the machine, 2 the work holder plate, 3 the lower part of the sewing machine head, 4 the label carrier, 5 the label retaining shoe or guide foot, and 6 the label slide or chute through which the label is delivered, all of which are substantially the same as the parts appearing in the Rosenthal patent above referred to and which it will not be necessary to here detail. Because my invention does not pertain to such details, I refer to the said patent for a 80 full understanding of the mechanism for stitching and affixing the label.

7 is the label follower disposed in the label chute 6 and has downwardly projecting fingers 8 which engage the rear edge of the 85 label and carry the same forward. A post 9 is secured to this slide extending upwardly therefrom.

On the post 9 is pivoted the latch lever 10 by pivot 11. An actuating spring 12 is secured to loop 10' on said lever, and is connected to post 13 on the said label carrier 4. Lever 10 is provided with an upwardly-extending finger hook 14 for convenient manipulation by the finger of the operator and is provided with a latch catch 15 on its under side that engages over the front end of the label chute to hold the label follower in retracted position.

On the side of the sewing machine head 3 100 is secured a stop arm 17 having a downwardly projecting portion 18 to engage the forward end 16 of the latch lever 10. The relation of these parts clearly appears in Figs. IV, V and VI in the different steps of 105 their operation.

An adjustable stop 19 is secured in place by the set screw 20 to limit the forward advance of the label follower.

From this description it is believed that 110 the functions of the various parts will be understood when the operation is definitely

pointed out. The sectional view of Fig. IV shows the machine after the stitching operation and after the label is removed ready to begin operations for the next label. The 5 operator by the hook 14 withdraws the latch lever 10 into engagement by catch 15 with the front end of the label chute 6, thereby withdrawing the label follower 7 into label receiving position. The label 21 is then 10 placed in the position seen in side view in Fig. V, and is ready to be fed under the label retaining shoe when the machine is manipulated.

The work holder plate and label shoe are 15 then elevated by means described and referred to in the said patent above referred to, and as the work holder plate rises the end 16 of the lever 10 contacts with the stop 17 in the position indicated by dotted lines 20 in Fig. VI. The end of the lever 16 then engages the downwardly projecting portion 18 of the stop 17 after the catch 15 is released from the front end of the label feeding chute, and a small advance motion is 25 permitted until the end 16 of the lever engages the downwardly projecting catch portion 18 and the preliminary label feed is stopped at that point. The catch 15 is then 30 on top of the chute in a disengaged position. When the machine has already been operated, the finished work with the label stitched thereon is withdrawn. A piece of work, as a garment to be labeled, is moved into place to receive the label.

35 At this juncture the foot of the machine is dropped down and, owing to the slight engagement of the end 16 of the lever by the catch 18, said end is immediately released and the label is shot under the label 40 retaining shoe while it is descending and is caught and held for the next stitching operation.

From this description it will be seen that 45 the machine is automatic to the extent of releasing the manually-operated devices so that the spring 12 performs its function of feeding the label at the proper time. As my invention does not relate to the parts which hold and stitch the label, I have not described the same in detail. My invention 50 might be used with various kinds of stitching devices, I having shown the same merely sufficiently in this connection for the purpose of explaining my invention, which is 55 an improvement merely in the step of feeding the label.

It will be observed that the spring 12 60 performs many functions in this behalf. It feeds the label follower; it actuates the lever so that it is latched in the withdrawn position; it also acts to actuate the lever so that it serves to move the label into its preliminary fed position. When the shoe 65 is dropped down it instantly shoots a label into place by actuating the label follower, as

has been already described. These functions could of course be accomplished by manipulation by hand, but they would not be so expeditiously done as by the use of this spring.

I therefore desire to claim the invention 70 specifically with the spring actuating means and also desire to claim the same broadly and specifically, as pointed out in the appended claims.

Having thus described my invention, what 75 I claim as new and desire to secure by Letters Patent is:

1. In a label feeding device, the combination with a sewing machine of a work shoe 80 and a label retaining shoe, of a label feed slide, a follower adapted to reciprocate in said slide, a latch lever pivoted to said follower, with a notch to engage the end of said slide, an actuating spring connecting a depending ear of the said lever and work shoe, 85 a stop secured to the head of the sewing machine projecting to engage the said lever to release the same preliminarily, and a catch on the said stop to engage and retain the lever on its preliminary release, positioned 90 to be disengaged from said lever by the lowering of the work shoe, whereby the spring will actuate the label follower and deliver the label under the label retaining shoe, co-acting as specified. 95

2. In a label feeding device, the combination with a sewing machine of a work shoe 100 and a label retaining shoe, of a label feed slide, a follower adapted to reciprocate in said slide, a latch lever pivoted to said follower, with a notch to engage the end of said slide, an actuating spring connecting a depending ear of the said lever and work shoe, and a stop secured to the head of the sewing machine projecting to engage the said lever 105 to release the same, whereby the spring will actuate the label follower and deliver the label under the label retaining shoe, coacting as specified.

3. In a label feeding device, the combination with a sewing machine of a work shoe 110 and a label retaining shoe, of a label feed slide, a follower adapted to reciprocate in said slide, a latch lever pivoted to said follower, with a notch to engage the end of said slide, an actuating spring connecting said lever and work shoe, a stop secured to the head of the sewing machine projecting to engage the said lever to release the same preliminarily, and a catch on the said stop to 115 engage and retain the lever on its preliminary release, positioned to be disengaged from said lever by the lowering of the work shoe, whereby the spring will actuate the label follower and deliver the label under the label retaining shoe, coacting as specified. 120

4. In a label feeding device, the combination with a sewing machine of a work shoe 125 and a label retaining shoe, of a label feed slide, a follower adapted to reciprocate in 130

- said slide, a latch lever pivoted to said follower, with a notch to engage the end of said slide, an actuating spring connecting said lever and work shoe, and a stop secured to 5 the head of the sewing machine projecting to engage the said lever to release the same, whereby the spring will actuate the label follower and deliver the label under the label retaining shoe coacting as specified.
- 10 5. In a label feeding device, the combination of a work shoe and a label holding shoe, of a label feed slide, a follower adapted to reciprocate in said slide, a latch on said fol-

lower to hold the same in withdrawn position to receive a label, a spring to move said follower to feed the label, and means for releasing the said latch automatically when the work shoe is lowered, as specified. 15

In witness whereof, I have hereunto set my hand and seal in the presence of two 20 witnesses.

MORRIS G. ROSENTHAL. [L. S.]
